UNITED STATES PATENT OFFICE.

AUGUST FILLGROVE, OF IRONTON, OHIO.

HYDROCARBON-HEATER.

SPECIFICATION forming part of Letters Patent No. 670,769, dated March 26, 1901.

Application filed November 12, 1900. Serial No. 36,237. (No model.)

To all whom it may concern:

Be it known that I, AUGUST FILLGROVE, a citizen of the United States, residing at Ironton, in the county of Lawrence and State of Ohio, have invented new and useful Improvements in Hydrocarbon-Heaters, of which the following is a specification.

This invention relates to new and useful improvements in hydrocarbon-heaters, and is especially adapted for use where it is desired to employ natural gas for heating purposes.

The primary object is to provide a device of simple construction which is adapted to thoroughly disintegrate the gas supplied thereto and which will consume all of the particles of the hydrocarbon and discharge hot air which is free of objectionable odors.

With this and other objects in view the invention consists in providing a casing having a feed-pipe therein, which is provided with a suitable number of burners arranged in alignment with each other and adapted to discharge the gas fed thereto upon oppositely-inclined deflectors which are arranged within the casing. These deflectors are secured to the walls of the casing and also extend transversely of said casing at the center thereof and are adapted to be heated by the gas-jets and will disintegrate the unconsumed particles of the gas escaping from the flame.

The invention also consists in certain novel features of construction and combination of parts, which will be hereinafter fully described and claimed, and illustrated in the accompanying drawings, showing the preferred form of my invention, and in which—

Figure 1 is a section on line $x-x$ of Fig. 2. Fig. 2 is a section on line $y-y$ of Fig. 1.

Referring to the drawings by numerals of reference, 1 is a casing, preferably formed of sheet metal and having an inlet 2, arranged in the front face thereof at a point above the bottom, and an outlet 3 in the front face adjacent to the top. The bottom 4 of the casing is preferably provided with a cover 5, of asbestos or other similar insulating material. An inwardly-extending flange 6 is arranged at the lower edge of the inlet 2 and is adapted to form a flue, whereby the air is conducted directly to the burners used within the apparatus. Parallel gas-distributing pipes 7 and 8 are arranged within the casing

adjacent to the bottom thereof and are connected at one end by means of an elbow 9 or in other suitable manner.

A feed-pipe (not shown) is adapted to be secured to the free end of the lower distributing-pipe 8, and a mixer 10 is provided at the free end of said pipe 8, whereby a mixture of gas and air may be discharged from the burners 11. These burners preferably comprise small tubes arranged upon the upper surface of the upper distributing-pipe 7, said burners being in alignment with each other.

A rectangular casing 12, formed, preferably, of sheet metal, is fitted within the heater between the inlet and outlet thereof, and secured to the inner surface of the front and rear walls of this casing are deflectors, each of which preferably comprises a straight body portion 13, which is adapted to be secured to the wall of the casing, and an inwardly-extending curved portion 14, which forms the deflector proper.

Additional deflectors 15 are arranged one above the other in the center of the casing and between the ends of the deflectors 14. Each of these deflectors 15 is preferably formed in one piece of sheet metal bent at the center and inclined in opposite directions, as shown in Fig. 2. Downwardly-extending flanges 16 are arranged at the ends of these deflectors, and said flanges are adapted to be secured to the side walls of the casing 12 in any suitable manner.

When gas is admitted to the distributing-pipes 7 and 8, the same first passes through the mixer 10, and this mixture of air and gas is discharged through the burners 11, where it is ignited in any suitable manner.

The jets of gas will thoroughly heat the inclined deflectors arranged thereabove, and the unconsumed particles which escape from the flames will upon contacting with the heated deflectors 14 and 15 be destroyed by combining with the surplus oxygen which is admitted through the inlets 2. The hot air discharged through the outlet 3 of the heater will thus be free of all noxious gases.

In the foregoing description I have embodied the preferred form of my invention; but I do not wish to be understood as limiting myself thereto, as I am aware that modi-

fications may be made therein without departing from the principle or sacrificing any of the advantages of this invention, and I therefore reserve to myself the right to make such changes as fairly fall within the scope thereof.

Having thus described the invention, what is claimed, and desired to be secured by Letters Patent, is—

- 10 In an apparatus of the character described, the combination with a casing having an inlet and an outlet; of a gas-distributing pipe, a burner extending therefrom, an inner casing secured within the casing of the heater,

inwardly-extending deflectors secured to the 15 opposite walls of the inner casing, transversely-extending oppositely-inclined deflectors secured to the end walls of the inner casing, and alternating with the remaining deflectors, said oppositely-inclined deflectors 20 being arranged above the burner and adapted to be heated thereby.

In testimony whereof I affix my signature in presence of two witnesses.

AUGUST FILLGROVE.
